Claims priority, application Australia Oct. 31, 1960
12 Claims. (Cl. 100—75)

This invention relates to multi-twin and multi-triple roller mills for crushing sugar cane for extracting the juice or sucrose.

The object of the invention is to provide a mill mechanically more efficient, which has a relative higher rate of crushing, is highly efficient, and is less expensive to install and operate than conventional two- or three-roller mills.

For example, under comparable conditions, the rate of crushing with mills according to the present invention is more than twice that with orthodox mills.

Due to the short distance between the centres of each pair of rolls (say approximately 9 feet) a much shorter building would suffice to accommodate a multi-twin roller crushing unit than is required for existing three roller mills with diffusion baths and intermediate carriers disposed between each crushing unit. Also due to the relatively higher rate of work, comparatively, the width of roller would be less than is commonly now in use.

Cost features in the above greatly favour multi-twin roller crushing units.

In a general form the invention is a sugar cane crushing mill comprising at least two spaced sets of crushing rollers, first means including spaced conveyors diverging forwards for feeding prepared cane to the inlet side of the first set of rollers, a first closed chute on the outlet side of each set of rollers adapted to receive the crushed cane from the adjacent set, second means including a second closed chute diverging forwards at approximately 5° for feeding crushed cane from each first closed chute to the next set of rollers, means for turning over the crushed cane at least partially during its passage from one set of rollers to the next and means for collecting expressed juice from the cane during and after its passage through each set of rollers.

By a "closed chute" is meant one which is closed at its top, bottom and sides. It is open at one end to receive crushed cane from the previous set of rollers and at its other end to allow crushed cane to pass towards the next set of rollers.

Some specific forms of the invention are shown in the accompanying drawings in which:

FIGURE 1 is a part perspective view of one form of the invention with some parts omitted for clarity;

FIGURE 2 shows an alternative means for feeding prepared cane to the first set of rollers;

FIGURE 3 is a view similar to that of FIGURE 1 but employing triple-roll sets instead of twin-roll sets;

FIGURE 4 is a typical vertical section at the left of the first set of rollers;

FIGURES 5 and 6 are detail views of alternative slatted belt constructions;

FIGURES 7, 8 and 9 are detail views of alternative roll axle spacing means;

FIGURE 10 is a detail view of roll grooving;

FIGURE 11 is a detail showing the rolls and juice trough arrangement;

FIGURES 12 and 13 are detail views of flanged and side-plated rolls;

FIGURE 14 is a detail of a grooved roll and associated scraper plate;

FIGURES 15 and 16 are detail views of a roll with juice grooves and an associated juice groove scraper;

FIGURE 17 is a fragmentary longitudinal section show-

2

ing a cane chute with fixed floor and a fixed and moving roof, and

FIGURE 18 is similar to FIGURE 17 but shows also means for feeding macerating fluid.

FIGURE 1 shows a typical arrangement of multi-twin rollers with a band conveyor feed 21, 22 to the first pair of rollers 23, 24 followed by the closed chute slat conveyor 25 and maceration fluid pipes 26 and 27. There follow the second pair of rollers 28, 29 with a closed feed chute 30 between each pair of rollers.

FIGURE 2 shows a variation of the position of the prepared cane feed bands 31, 32 in relation to the first pair of rollers. It shows these bands inclined from the horizontal in a position to feed the prepared cane downwards and forwards to the first pair of rollers and thereafter having all other aspects similar to what is shown and described for FIGURE 1.

FIGURE 3 shows the application of the closed chute to a typical three roller mill 33, 34 and 35 with a short closed chute 36 provided with maceration fluid pipes 37 on the discharge side of rollers 33 and 35 set to deliver crushed cane or bagasse upwards and forwards to mechanically driven two-band or two-slat conveyors 40, 41 feeding to front and top rollers 42, 43 of the next three roller mill of a tandem.

A particular form of the invention will now be described having two rollers in each set disposed with their axes approximately horizontal one above the other. In this particular case there are four pairs of rollers (FIGS. 1 and 2) but there could be more pairs or fewer down to two pairs of rollers.

The prepared cane, ready for crushing, is fed as in FIGURE 1 horizontally and forward, or as in FIGURE 2 downwards and forwards on the incline of a closed chute in each case formed by the forward runs of two spaced band conveyors 21, 22 or 31, 32 running between fixed side plates 44 (FIGURE 4) which prevent spillage and assist in building up a slight feed pressure to the rollers. Each band has attached to its outer face spaced transverse gripping strips 45 (FIGURE 5) to assist the rate of feeding between the bands; lipped slats 46 (FIGURE 6) may be used as an alternative. The band pulleys 47, 48 illustrated in FIGURES 1 and 2 are larger at the prepared cane entry end than those at the discharge end. The reason for the smaller pulleys 48 at the discharge end is to bring the prepared cane as close to the crushing rolls as is possible. The bands may be driven as circumstances permit from either the entry or discharge end pulleys.

The bands diverge slightly in a vertical plane from entry end to discharge end to avoid chokage of the feed between the bands.

The bands are driven at speeds in excess of the surface speed of the crushing rollers to ensure a satisfactory high rate of feeding to the nip of the crushing rollers and to maintain a slight build up of pressure of the feed against the two crushing rollers.

The roller axle spacing may be varied. This may be done by forcing between the roller axle bearing blocks 49, wedges 50 (FIGURE 7) or packing piece 51 (FIGURE 8) or by screws 52 (FIGURE 3).

Each roller is formed with axially spaced circumferential V grooves, respective crests of one roller being aligned with the troughs of the other so that, when the roller axle spacing is least, each crest of one roller almost fills the corresponding trough of the other. In special circumstances and where it can be conveniently used circumferential V grooves may be varied. In FIG. 10, e.g. where the opening between the top and bottom rollers 23, 24 is always positive, the groove pitch on one may differ from that on the other. Each roller is driven at a convenient speed.

Juice expressed from the cane (or bagasse) as the latter

is crushed between the rollers is drained to a bed plate juice trough 53 (FIG. 11). The top roller of the pair of rollers should have flanges 54 (FIG. 12) fitted to its ends as this is considered an aid to good crushing. Otherwise close fitting side plates 55 (FIG. 13) at the rollers would be required and this may be readily arranged where a mild steel fabrication is used as a frame instead of cast steel or cast iron mill cheeks.

On the exit side of the rollers there are adjustable top and bottom scraper plates 56 (FIG. 14) (part of a closed feed system to the next pair of rollers) which have teeth 57 so cut as to fit into the grooves of the rollers and remove the crushed cane embedded in the grooves. The bottom rollers 24 have narrow juice grooves 58 (FIG. 16) cut at the bottom of the V grooves to assist extraction of juice and these grooves are kept clean by fixed knife scrapers 59 (FIG. 15).

The crushed cane with less sugar juice now passes through a closed chute diverging at approximately 5° forwardly, the top plate 56 of which is cut short to provide for a mechanically driven lipped slat conveyor 25 again driven through either a large diameter rearward pulley or a smaller forward pulley for similar reasons as stated for the band conveyors 21, 22 in FIG. 1. This conveyor 25 runs at a slightly higher speed than the peripheral speed of the crushing rollers 28, 29 it is feeding. The band 25 on its lower run travels horizontally and its use is designed to move the crushed cane at the top of the chute along to the next pair of rolls at a faster rate than the main body of the crushed cane or bagasse. The fixed bottom plate 60A is stepped down at 60 (FIG. 17) to delay further the forward movement of the lower crushed cane compared to the main body of crushed cane or bagasse between the upper and lower layers. Where the sets of rollers are widely spaced two or more spaced steps 60 may be provided. This speed variation through the cross section of the mass of crushed cane or bagasse re-orientates the crushed cane or bagasse fibre at the top and bottom of the cross section in each closed chute to the next pair of rollers and thus assists the further extraction of juice or sucrose. In its passage through the closed chute between successive sets of rollers, the mass of bagasse is reduced in density by being teased out and reoriented by the relatively high speed upper band 25 and the stepped chute floor.

It has been found by experiment that further extraction of juice from the teased bagasse as it passes through the next set of rollers is greater than if the bagasse had remained in a compact high density condition.

In some circumstances the fixed stepped plate 60A may be dispensed with and a lower conveyor, generally similar to the upper conveyor 25, substituted. This arrangement is similar to that of FIG. 3.

Provision is made for the application of macerating fluids under pressure through a V channel 61 (FIG. 18) cut across the inside surfaces of the top plate 56, bottom plate 60A and both side plates 64 of the closed chute and the maceration pipes 26, 27 are connected externally through suitable holes to the V grooves. This provision is designed so that a comparatively low density fluid may penetrate at least the outer layer of the crushed cane passing along the chute.

Experiments have shown that the outside of the crushed cane from the rollers contains higher density juice than the inner section of the crushed cane. The dilution effect assists the extraction of sucrose during crushing between the rollers.

The crushed cane (generally known as bagasse) passes successively through a second pair of rollers similar and similarly mounted and driven to the first pair, through a similar chute with fixed sides and floor (stepped) and having a fixed roof at its rearward end and a moving roof at its forward end as before and then to the next pair of rollers and so on.

Where convenient conventional sets of existing three roller units may be retained and the closed feed system installed (FIG. 3) between each set of three rollers. There are two horizontally spaced rollers 34, 35 and one upper one 33 between the lower two. The cane passes between the upper roller 33 and the rearward lower roller 34 and between the upper 33 and the forward lower roller 35. A narrow trash plate 65 extends between the lower rollers over which the cane or bagasse passes. The chute 36 is closed at its top, bottom and sides.

This arrangement, whilst making use of existing crushing rollers, would not have all of the advantages outlined above for multi-twin rollers.

15 Experiments with a small multi-twin roller crushing unit resulted in a cane fibre rate of nearly 5.0 tons per foot width of roller per hour (t.f.f.h.). Had more power for driving been available a much higher rate would have been attained.

20 Previous experiments with a small experimental crushing unit showed that the fibre rate attained was more than doubled when large commercial crushing units were manufactured and installed.

25 A similar relationship would no doubt exist between this small multi-twin roller plant and a larger commercial unit and if realised a cane fibre rate of 10.0 t.f.f.h. or more could be expected.

30 The high rate of work combined with high efficiency of operation would enable the cost of construction of cane sugar mills to be greatly reduced as the length of the rollers and diameter of shaft bearings would be much less than currently required for three roller mills and labour and production costs would be considerably reduced.

35 The number of rollers in use at present in most crushing stations of cane sugar factories could be reduced by the use of multi-twin roller crushing mills thereby lowering capital cost and maintenance.

What I claim is:

1. A sugar cane crushing mill comprising at least two spaced sets of crushing rollers for feeding crushed cane through said rollers, first means for feeding prepared cane adapted for being crushed to the first set of rollers, the latter means including spaced moving conveyors diverging in the direction of feed of the cane towards the rollers and having a linear speed exceeding the peripheral speed of the rollers to cause the prepared cane to be fed under pressure to the first set of rollers, each set of rollers having an inlet and an outlet side, a closed chute on the outlet side of each set of rollers for receiving crushed cane from the associated set, each closed chute diverging from the outlet side of the associated set of rollers in a direction away therefrom, second means including a second closed chute between each of the first said closed chutes and the next set of rollers for receiving crushed cane from the first closed chute for feeding the crushed cane to the next set of rollers while reorienting and teasing out the crushed cane, said second means including a conveyor in said second closed chute having a linear speed in a direction towards the next set of rollers which is greater than the peripheral speed of the rollers, for advancing a surface layer of the crushed cane which is in contact with the latter conveyor at an increased speed towards the next set of rollers, adjacent first and second chutes defining a step opposite the conveyor in said second closed chute for increasing the section of travel of the crushed cane whereby the advance of the crushed cane in a surface layer opposite the first said surface layer will be decreased as the crushed cane passes said step, the mill further comprising means for collecting expressed juice from the cane during and after passage thereof through each set of rollers.
2. A mill as in claim 1 wherein the first feeding means comprises spaced side walls forming with the said spaced diverging conveyors another substantially closed chute

75 70 75

and means for driving the conveyors so that the same advance towards the first set of rollers.

3. A mill as in claim 2 wherein the said conveyors of the first means are approximately horizontal.

4. A mill as in claim 2 wherein the said conveyors of the first means slope downwards towards the first set of rollers.

5. A mill as in claim 1 wherein the rollers of each set are provided with circumferential grooves and at least one scraper plate for each roller on the outlet side thereof, each plate having an edge adjacent the roller provided with spaced teeth adapted to enter the respective roller grooves to scrape the same.

6. A mill as in claim 5 wherein one scraper plate is provided for each roller on the outlet side of the set and the scraper plates form the respective top and bottom walls of the first closed chute.

7. A mill as in claim 5 wherein narrow juice grooves are provided at the bottom of the main grooves of the bottom roller on the outlet side of the set and a knife scraper having spaced teeth adapted to enter the respective juice grooves to clean the same.

8. A mill as claimed in claim 1 wherein the second chutes each have a roof constituted by said conveyor thereof, adjacent first and second chutes including a stationary continuous floor extending along both chutes and including said step which is located below the conveyor of the second means at the beginning thereof such that an upper surface layer of the crushed cane is moved more rapidly than the remainder of the crushed cane and a lower surface layer of the crushed cane is moved more slowly than the remainder of the crushed cane whereby the crushed cane undergoes a turning over and reorientation.

9. A mill as in claim 1 wherein the second closed 35

chute has a roof and floor between adjacent sets of rollers, the lower run of an upper band conveyor and the upper run of a lower band conveyor respectively constituting the roof and floor of the second closed chute, the said lower run being spaced above the said upper run, the latter conveyors extending between the associated first closed chute and the next set of rollers and means for driving the said conveyors so that the said lower and upper runs move towards the next set of rollers, the conveyors comprising means for turning over the crushed cane.

10. A mill as in claim 9 wherein the roof and floor of the second closed chute between adjacent sets of rollers diverge towards the next set of rollers in an approximately vertical plane.

11. A mill as in claim 1 including means for feeding macerating fluid to each first closed chute.

12. A mill as in claim 1 wherein the two sides of each set of rollers are closed to provide a substantially closed 20 passage for the cane through each set of rollers.
